DESIGN FOR A TIRE

John E. Allen, Chicopee Falls, Mass., assignor to
The Fisk Rubber Corporation, Chicopee Falls,
Mass., a corporation of Delaware

Application June 11, 1937, Serial No. 69,803

Term of patent 14 years

To all whom it may concern:

Be it known that I, John E. Allen, a citizen of the United States, residing at Chicopee Falls, county of Hampden, and Commonwealth of Massachusetts, have invented a new, original, and ornamental Design for a Tire, of which the following is a specification, reference being had to the accompanying drawing, forming part thereof.

In the drawing,

Fig. 1 is a perspective view of a tire, only a por-

tion thereof being in full lines, showing my new design;

Fig. 2 is a fragmentary plan view of the tire; and

Fig. 3 is a sectional view substantially on line 3—3 of Fig. 2.

I claim:

The ornamental design for a tire, as shown.

JOHN E. ALLEN.
